UNITED STATES PATENT OFFICE

94,135

DESIGN FOR A MEMORANDUM BOOK COVER

Lurelle Guild, Noroton, Conn., assignor to Kensington, Incorporated, New Kensington, Pa., a corporation of Pennsylvania

Application October 11, 1934, Serial No. 53,551

Term of patent 3½ years

To all whom it may concern:

Be it known that I, Lurelle Guild, a citizen of the United States, residing at Noroton, in the county of Fairfield and State of Connecticut, have invented a new, original, and ornamental Design for a Memorandum Book Cover, of which the following is a specification, reference being had to the accompanying drawing, forming a part thereof.

Fig. 1 is an end view and Fig. 2 is a side or front view of a memorandum book cover embodying my new invention.

I claim:

The ornamental design for a memorandum book cover as shown.

LURELLE GUILD.
